Filed Dec. 11, 1970, Ser. No. 26,409

Term of patent 14 years

Int. Cl. D6—05

U.S. Cl. D92—21

FIG. 1

FIG. 3

FIG. 1 is a top plan view of a throw rug showing my new design;

FIG. 2 is a side elevational view thereof;

FIG. 3 is a bottom plan view;

FIG. 4 is a top plan view of another embodiment of the design of FIG. 1;

FIG. 5 is a side elevational view thereof; and

FIG. 6 is a bottom plan view.

The characteristic feature of my design resides in the toe like configurations on the opposite narrower ends of the throw rug all as shown on the drawing.

I claim:

The ornamental design for a throw rug, substantially as shown and described.
